UNITED STATES PATENT OFFICE.

CHARLES SPIRO, OF NEW YORK, N. Y.

TELEGRAPH-CALL.

1,215,734.

Specification of Letters Patent. Patented Feb. 13, 1917.

Application filed April 6, 1916. Serial No. 89,325.

To all whom it may concern:

Be it known that I, CHARLES SPIRO, a citizen of the United States, residing at New York, in the county of New York and State 5 of New York, have invented certain new and useful Improvements in Telegraph-Calls, of which the following is a specification.

This invention relates to a telegraph call and particularly to a construction wherein 10 the call is automatically transmitted by mechanical means and may be repeated.

The invention has for an object to provide a novel and improved construction by which upon the depression of a key lever the calling 15 disk will be brought into electrical circuit and continuously rotated for a number of times to insure the accurate and repeated sending of the call or signal for any predetermined telegraph station.

20 A further object of the invention is to provide improved means by which more than one series of call disks may coöperate with a single set of key levers by a longitudinal shifting of the disks relative to the 25 contact members controlled by the key levers whereby the calling capacity of the machine may be increased to a large extent.

Another object of the invention is to present a novel construction of contact mechanism coöperating with each disk whereby 30 the former is operated by a key lever to make contact with a disk, automatically held in such position, and automatically released and contact broken when the disk has completed its travel.

35 A further object of the invention is to provide an improved form of call disk which is held against rotation upon its shaft and may be arranged by the operator to send any desired call or signal.

Other and further objects and advantages of the invention will be hereinafter set forth and the novel features thereof defined by the appended claims.

45 In the drawings—

Figure 1 is a top plan of the machine;

Fig. 2 is a vertical section thereof on line 2—2 of Fig. 1;

Fig. 3 is a top plan of the rocking beam;

50 Fig. 4 is a central longitudinal section; on line 3—3 of Fig. 2.

Fig. 5 is a detail plan of the disk shaft;

Fig. 6 is a similar view of the disk locking bar; and

Fig. 7 is an elevation of one of the call 55 disks.

In the drawings like numerals refer to like parts in the several views thereof.

The numeral 10 designates the frame of the machine which may be of any desired 60 construction and configuration. This is provided at each end of the upper portion with bearings 11 insulated from the frame and adapted to receive a disk supporting rod 12 mounted therein for rotation and provided 65 with a circuit connection 13. This rod has mounted thereon a disk retaining shaft or sleeve 13 of square or angular formation and adapted to be shifted longitudinally of the rod while held against relative rotation. 70 The shaft may be retained against rotation on the rod and held in its shifted position thereon by any desired means, for instance, a spring detent 14 carried thereby to engage a seat or recess 15 in the rod 12. 75

This shaft or sleeve, as shown in Fig. 5, is formed upon its opposite sides with a series of parallel grooves 16 arranged to receive and separate in proper alignment the series of contact or call disks 17 when 80 mounted thereon. This call disk, as shown in Fig. 7, is formed with a angular slot or recess 18 so that the walls 19 thereof may enter the grooves 16 to hold the disk against rotation upon its shaft. These walls 19 are 85 formed with laterally disposed guide slots 20 extending therefrom toward the periphery 21 of the disk. This outer edge or periphery of the disk is provided with a continuous series of spaced lugs or cuts 22 90 extending inward therefrom to form an intermediate series of contacts 23, any one or more of which may be removed or bent backward to form the proper sending or call characters upon the disk. For example, if the telegraphic dot and dash system be used each contact will be equivalent to a dot signal and when two adjacent contacts are left in position the dash signal is formed. This permits a stock disk to be used from which 95 any desired signal may be formed, or the same signal repeated a number of times upon the periphery of the disk.

The guide slots 20 coöperate with a locking bar 25, shown in detail in Fig. 6, formed 100 with a series of notches or recesses 26 in its opposite side edges 27. These edges enter the slots 20 when the bar is shifted lon-

gitudinally to lock the disks in position upon the sleeve. The bar may be mounted in any desired manner, for instance, upon the under face of the angular shaft or sleeve 13 by means of headed fastenings 28 extending through slots 29 in the bar and entering the body of the sleeve, as shown in Fig. 4. One end of the bar may also be provided with an operating lip or handle 30 for shifting the same. It will be seen that when the notches 26 are in alinement with the grooves 16 on the shaft the call disks may be slipped into position and then locked by shifting the bar to bring the notches out of alinement.

Each call disk coöperates with a contact lever 31 pivotally mounted upon a cross rod 32 mounted at its opposite ends in insulated bearings 33 carried by the frame 10. The vertical arm 34 of this lever is provided with a contact spring 35 secured thereto at 36 from which point a circuit connection 37 extends to a binding post 38 upon the frame. The lever 31 is formed with a rearwardly extending tail 39 from which a tension spring 40 extends to a cross bar 41 of the frame for the purpose of normally retaining the lever out of contact with the disk. The lever is also provided with a forwardly extending operating arm 42, the vertical movement of which is limited by a cross rod 43.

This operating arm may be depressed to make contact by any desired form of key lever 44, for instance, pivoted at 45 and normally held in elevated position by a spring 46. The key lever is formed with a hook or riser 47 having its upper end 48 releasably engaging the free end of the operating arm 42. The finger piece 49 of the key lever is provided with a removable cap or cover 50 adapted to inclose and retain the indicating characters corresponding to the disk disposed to coöperate therewith and permit such characters to be changed when other disks are used. The depression of the key lever carries downward the operating arm therewith and said lever is adapted to be restored independently thereof.

When the operating arm is depressed the tail of the contact lever is raised and the holding bail or member 51 released to automatically swing beneath said tail and retain the contact lever against the disk, as shown by dotted lines in Fig. 2. The bail member is pivoted at 52 and forced inward by a spring 53. It is also formed with a restoring lug 54 disposed above a rocking beam 55 pivoted at 56 and having at one end a lever 57 adapted to be engaged by a moving part to rock the beam.

For the purpose of rotating the disks by their supporting shaft, a driving lever 58 is pivotally mounted at 59 and provided at one side of its pivot with a bail 60 extending

beneath all the key levers. This driving lever carries at its opposite end a sector 61 which is normally held in lowered position by the spring 62 extending therefrom to the frame. This sector is geared in any desired manner to cause a number of revolutions of the disk during its travel downwardly which produces a repeated or continuous sending of the call. One form of gearing comprises a pinion 63 meshing with the sector and carrying on its shaft a gear 64, which in turn meshes with a gear 65 rotatable upon the rod 12 and connected thereto for movement in one direction by a pawl and ratchet 67. This prevents a reverse movement of the disk as the sector is raised. In order to secure an even rotation of this rod under the spring driving tension, a regulating device, such as a fly wheel 24 may be secured thereon to rotate therewith.

The sector before completing its downward travel under the influence of the spring 62 engages and rocks the beam 55 against the lug 54 thus forcing outward the holding member and permitting the contact member to be withdrawn from the disk by its restoring spring to cease sending the call. The electrical connections shown may be arranged in any desired relation to a telegraphic transmitter or receiver, but these parts are not illustrated as they form no part of this invention. Any desired number of key levers may be used in the machine but as they are duplicated only one thereof with its connections has been specifically described. The machine however provides for the use of the minimum number of keys with a larger number of call disks by shifting the latter relative to the key operated contact member, and under such conditions each finger piece will contain characters indicating two or more calls. When the disks are changed these characters are correspondingly changed by removing the cap upon the finger piece. By separately restoring the key lever and thus disconnecting the contact lever therefrom during the call sending action, the rotating means for the disk is relieved of the resistance of the key lever in its upward travel and the spring driven geared connection for repeatedly rotating the disk permitted to impart the greatest number of rotations thereto.

In the operation of the invention the desired disk is arranged to produce the call by removing the proper portions thereof and placed in the grooves upon the squared shaft where it is locked in position by the sliding bar. The key lever coöperating with the disk is provided with a character corresponding to the call thereon. Upon depression of this key lever the operating arm of the contact lever is drawn downward therewith and the contact spring brought against the disk to establish electrical con-

tact therewith. This same action swings the driving sector upward and places its spring under tension before the contact lever reaches the disk. As contact is made the holding member is released by the sector and forced inward by its spring beneath the tail of the contact lever and the parts thus maintained in contact during the entire rotation of the disk. When pressure is removed from the finger piece of the key lever it is elevated by its spring, leaving the operating arm in lowered position, and the sector begins its downward driving action which through its geared connection causes a continued rotation of the shaft bearing the disk to transmit a succession of repeated calls. As the sector approaches the lower end of its travel it contacts with the rocking beam which through its connection with the holding member throws the latter from beneath the tail of the contact lever and holds said member in this position while the sector is lowered. This lever is automatically withdrawn from the disk and the parts are brought to rest. It will be noted that the contact, holding and releasing actions, as well as the driving of the disk, are automatically performed through the simple depression of a key and no further action or attention by the operator is required. This particularly adapts the invention for use in small telegraph stations where the operator often has many other duties to perform and prevents the inconvenience and loss of time required in repeatedly transmitting a telegraph call by hand and insures an accurate sending of the call.

While a number of the details of this mechanism have been specifically described the invention is not confined thereto as changes may be made therein without departing from the spirit of the invention as defined by the claims thereon.

What I claim is:—

45 1. In a telegraph call, a rotatable call disk having contacts thereon, a coöperating contact lever, key operated means for moving said lever into contact with said disk, and means for actuating the latter for a plurality of rotations by a single operation of said key operated means.

2. In a telegraph call, a rotatable disk, a coöperating contact lever, means for rotating said disk, key operated means for actuating said lever and rotating means whereby the disk may be successively rotated by a single operation of said key operated means to effect a plurality of calls, and means for automatically retaining said lever in contact with said disk during the continued revolutions thereof.

3. In a telegraph call, a rotatable disk, a coöperating contact lever, means for rotating said disk, key operated means for actuating said lever and rotating means where-

by the disk may be successively rotated by a single operation of said key operated means to effect a plurality of calls, means for automatically retaining said lever in contact with said disk, and means actuated by said rotating means for releasing said retaining means. 70

4. In a telegraph call, a rotatable disk, a coöperating contact lever, means for rotating said disk, key operated means for actuating said lever and rotating means whereby the disk may be successively rotated by a single operation of said key operated means to effect a plurality of calls, means for automatically retaining said lever in contact with said disk, means directly actuated by said rotating means for releasing said retaining means, and means for automatically breaking contact between said lever and disk when the former is released. 80 85

5. In a telegraph call, a rotatable disk, a coöperating contact lever, means for rotating said disk, key operated means for actuating said lever and rotating means whereby the disk may be successively rotated by a single operation of said key operated means to effect a plurality of calls, means for automatically retaining said lever in contact with said disk, means actuated by said rotating means for releasing said retaining means, means for automatically breaking contact between said lever and disk when the former is released, and means for restoring said key operated means independent of the contact lever. 90 95 100

6. In a telegraph call, a shaft provided with a call disk, a key lever, means actuated thereby for rotating said shaft, and a contact lever detachably connected with said key lever to be moved thereby into contact- 105

7. In a telegraph call, a shaft provided with a call disk, a key lever, means actuated thereby for rotating said shaft, a contact lever detachably connected with said key lever to be moved thereby into contacting position with said disk, and means for restoring said key lever after depression independently of said contact lever. 110

8. In a telegraph call, a shaft provided with a call disk, a key lever, means actuated thereby for rotating said shaft, a contact lever adapted to be actuated to engage said disk by said key lever during its downward travel, a holding member independent of the key lever to retain said contact lever and disk in circuit, and means carried by the key lever to release said contact lever after said downward movement of the key lever. 120 125

9. In a telegraph call, a shaft provided with a call disk, a key lever, means actuated thereby for rotating said shaft, a contact lever adapted to be actuated in one direction by said key lever, a holding member to retain said contact lever and disk in circuit, 130

- and means actuated by said rotating means for withdrawing said holding member.
10. In a telegraph call, a shaft provided with a call disk, a key lever, means actuated thereby for rotating said shaft, a contact lever adapted to be actuated by said key lever, and a pivoted spring actuated holding member adapted to be released by said rotating means and to engage and retain said contact lever in circuit.
11. In a telegraph call, a shaft provided with a primary and secondary series of call disks, the latter being entirely at one side of the former, contact means coöperating with the entire primary series of said disks, means for rotating said disks and actuating said contact means, and means for shifting said secondary series of disks into operative alinement with said contact means.
12. In a telegraph call, a shaft provided with a call disk, a key lever, means actuated thereby for rotating said shaft, a contact lever adapted to be moved to engage said disk by pressure upon said key lever during its downward travel, and means for retaining said contact lever and disk in circuit.
13. In a telegraph call, a shaft provided with a sleeve, a primary and secondary series of call disks removably mounted upon said sleeve, one of said series being disposed entirely at one side of the other, contact means coöperating with one series of said disks, means for rotating said shaft and actuating said contact means, and means for shifting and retaining said sleeve longitudinally upon said shaft.
14. In a telegraph call, a rotatable shaft, a call disk mounted thereon, a contact lever coöperating with said disk and having a forwardly extending operating arm, a key lever provided with a hooked riser engaging the free end of said operating arm, and means actuated by said key lever for rotating said shaft.
15. In a telegraph call, a rotatable shaft, a call disk mounted thereon, a contact lever coöperating with said disk and having a forwardly extending operating arm, a key lever provided with a hooked riser engaging the free end of said operating arm, means actuated by said key lever for rotating said shaft, a rearwardly extending tail upon said contact lever, and a holding member adapted to swing beneath said tail when said contact lever is in circuit with said disk.
16. In a telegraph call, a rotatable shaft, a call disk mounted thereon, a contact lever coöperating with said disk and having a forwardly extending operating arm, a key lever provided with means engaging the free end of said arm, means actuated by said key lever for rotating said shaft, a rearwardly extending tail upon said contact lever, a holding member adapted to swing beneath said tail, and means actuated by said rotat-
- ing means for withdrawing said holding member.
17. In a telegraph call, a rotatable shaft, a call disk mounted thereon, a contact lever coöperating with said disk and having a forwardly extending operating arm, a key lever provided with means engaging the free end of said arm, means actuated by said key lever for rotating said shaft, a rearwardly extending tail upon said contact lever, a holding member adapted to swing beneath said tail, means actuated by said rotating means for withdrawing said holding member, means for automatically restoring said contact lever, and means for independently restoring said key lever.
18. In a telegraph call, a rotatable shaft, a call disk mounted thereon, a contact lever coöperating with said disk and having a forwardly extending operating arm, a key lever provided with means engaging the free end of said arm, means actuated by said key lever for rotating said shaft, a rearwardly extending tail upon said contact lever, a pivoted spring pressed holding bail adapted to be operated in one direction by said tail and to swing beneath the same, and means actuated by said rotating means to engage and withdraw said holding bail.
19. In a telegraph call, a rotatable shaft, a call disk mounted thereon, a contact lever coöperating with said disk and having a forwardly extending operating arm, a key lever provided with means detachably engaging said arm for depression thereof, a driving lever provided with a bail disposed beneath said key lever, and a geared connection from said driving lever to said shaft.
20. In a telegraph call, a rotatable shaft, a call disk mounted thereon, a contact lever coöperating with said disk, a key lever provided with a detachable connection for operating said contact lever, a driving lever provided with a bail disposed beneath said key lever and a sector gear at its opposite end, and a geared connection from said sector to said shaft arranged to effect a plurality of revolutions thereof to transmit repeated calls.
21. In a telegraph call, a rotatable shaft, a call disk mounted thereon, a contact lever coöperating with said disk, a key lever provided with means for operating said contact lever, a driving lever provided with a bail disposed beneath said key lever and a sector gear at its opposite end, a geared connection from said sector to said shaft, a holding member adapted to engage said contact lever and formed with a restoring lug, and a rocking beam adapted to engage said lug and sector to release said holding member.
22. In a telegraph call, a rotatable shaft, a call disk mounted thereon and provided with duplicated call members, a contact lever coöperating with said disk, a key lever

provided with means for operating said contact lever, a driving lever adapted to be operated in one direction by said key lever, a spring for returning said driving lever, and a geared connection therefrom to said shaft arranged to effect a plurality of revolutions thereof to transmit repeated calls.

23. In a telegraph call, a rotatable shaft, a call disk mounted thereon, a contact lever coöperating with said disk, a key lever adapted to operate said contact lever, a driving lever adapted to be operated in one direction by said key lever, a spring for returning said driving lever, a geared connection therefrom to said shaft, a holding member disposed to engage said contact lever and provided with restoring means, and means arranged to engage said driving lever during its travel and to actuate said restoring means.

24. In a telegraph call, a rotatable shaft, a call disk mounted thereon, a contact lever coöperating with said disk, a key lever adapted to operate said contact lever, means actuated by said key lever for rotating said shaft, a pivoted holding bail disposed to engage said contact lever and provided with a restoring lug, a spring for forcing said bail toward said contact lever, and a rocking beam arranged to engage said restoring lug and the key actuated rotating means.

25. In a telegraph call, a rotatable shaft, a call disk mounted thereon, a contact lever having an arm disposed to engage said disk, a laterally extending operating arm at one side thereof, and a holding tail disposed at the opposite side thereof, and means for operating said contact lever.

26. In a telegraph call, a rotatable shaft, a call disk mounted thereon, a contact lever having an arm disposed to engage said disk, a laterally extending operating arm at one side thereof, and a holding tail disposed at the opposite side thereof, key controlled means for operating said lever toward the disk, a restoring spring for said lever, a holding member mounted to engage said tail, and means for withdrawing said member from said tail.

27. In a telegraph call, a rotatable shaft, a call disk mounted thereon, a contact lever having an arm provided with a contact spring disposed to engage said disk, a forwardly extending operating arm at one side thereof, and a holding tail having a tapering upper face disposed at the opposite side thereof, means for operating said contact lever, and means to engage said tail.

28. In a telegraph call, an angular shaft provided with oppositely disposed grooves, a slotted call disk adapted to seat in said grooves, circuit means adapted to engage said disk, and means for rotating said shaft.

29. In a telegraph call, an angular shaft provided with oppositely disposed grooves,

a slotted call disk adapted to seat in said grooves, circuit means adapted to engage said disk, means for rotating said shaft, and means carried by said shaft for locking said disk thereon.

30. In a telegraph call, an angular shaft provided with oppositely disposed grooves, a slotted call disk adapted to seat in said grooves and provided with a locking recess, circuit means adapted to engage said disk, means for rotating said shaft, and a slide bar mounted upon said shaft and adapted to enter said recess to lock said disk.

31. In a telegraph call, an angular shaft provided with a series of oppositely disposed grooves, slotted call disks seated in said grooves, circuit means adapted to engage said disks, means for rotating said shaft, and a slide bar secured upon said shaft and having a series of recesses in its opposite edges, said edges being adapted to enter guide recesses at the opposite sides of the slot in the disks.

32. In a telegraph call, a rotatable shaft provided with oppositely disposed grooves having parallel inner walls, a slotted call disk adapted to seat in said grooves, circuit means adapted to engage said disk, and means for rotating said shaft.

33. In a telegraph call, a rotatable shaft provided with oppositely disposed grooves having parallel inner walls, a slotted call disk adapted to seat in said grooves and formed with opposite locking recesses, circuit means adapted to engage said disk, a locking bar slidably mounted upon said shaft and having opposite notches in its side walls, and means for rotating said shaft.

34. In a telegraph call, a rotatable supporting rod, a disk shaft secured thereon and provided with a series of oppositely disposed grooves, call disks mounted in said grooves, circuit means adapted to engage said disks, and means for rotating said rod.

35. In a telegraph call, a rotatable supporting rod, a disk shaft secured thereon and provided with a series of oppositely disposed grooves, call disks mounted in said grooves, means for shifting said shaft longitudinally upon said rod, circuit means adapted to engage less than the entire number of said disks, and means for rotating said rod.

36. In a telegraph call, a call disk provided with a series of spaced kerfs extending inward from the periphery thereof to form removable contact portions.

37. In a telegraph call, a slotted call disk provided with lateral locking recesses extending from the side walls of said slot.

38. In a telegraph call, a slotted call disk provided with lateral locking recesses extending from said slot and with a series of spaced kerfs extending inward from the

periphery thereof to form removable contact portions.

39. In a telegraph call, a rotatable shaft provided with a plurality of call disks, contact means coöperating with less than the entire number of said disks, key levers for controlling said disk rotation and said contact means, means for shifting said disks laterally of the contact means, and a removable finger cap for said key levers adapted to retain indicating characters for more than one of said disks.

40. In a telegraph call, a rotatable call

disk provided with more than one complete call signal thereon, a coöperating contact 15 lever, key operated means detachably connected with said lever for moving the same into contact with said disk, and means for actuating the latter for a plurality of rotations by a single operation of said key lever. 20

In testimony whereof I affix my signature in the presence of two witnesses.

CHARLES SPIRO.
